UNITED STATES PATENT OFFICE.

LUCIAN E. PARKER, OF WADSWORTH, OHIO, ASSIGNOR TO THE OHIO MATCH COMPANY,
OF WADSWORTH, OHIO, A CORPORATION OF OHIO.

BOOK-MATCH.

1,154,586.

Specification of Letters Patent. Patented Sept. 21, 1915.

Application filed November 27, 1914. Serial No. 874,205.

To all whom it may concern:

Be it known that I, LUCIAN E. PARKER, a citizen of the United States, residing at Wadsworth, in the county of Medina and State of Ohio, have invented a certain new and useful Improvement in Book-Matches, of which the following is a full, clear, and exact description.

A common and well-known form of match holder, to be carried in one's pocket, comprises a folded strip of paper to which matches in card form are secured and inclosed by folding a free end flap of the strip down over the matches and tucking the end of this flap in under an overlapping portion of the strip on which the striking surface is applied. These holders are of wedge form in side view. Matches so arranged are known as book matches.

The object of this invention is to provide a compact book of few parts, easy to manufacture, and capable of containing a quantity of accessible matches, and having convenient striking surfaces which are so placed as to eliminate accidental firing, and at the same time to leave a large amount of space for advertising; and also a book wherein a metallic staple is used for the double purpose of fastening on the card of matches and for holding down the flap when the book is closed; and also a book of parallel rather than wedge form, when folded, whereby the books may be conveniently packed into packages without expensive or elaborate machinery and of such construction that it may readily be used for a comparatively few matches or for a comparatively large number of matches.

The invention consists of a cover or holder strip, having two substantially equal parts, and a third closing flap, all connected by hinge members integral therewith, and having cards of matches applied to one or both of the equal parts; a metallic fastening staple being used for the double purpose of fixedly and immovably securing one of the cards to the cover or holder strip and of affording a clip for securing the flap or closing member when the book is folded or in closed condition, all as I will proceed now to explain and finally claim.

In the accompanying drawings illustrating the invention, in the several figures of which like parts are similarly designated, Figure 1 is a plan view of one form of the

device open, Fig. 2 is an inverted plan view; and Fig. 3 is a plan view of the device closed, Fig. 4 is an inverted plan view thereof, and Fig. 5 is a side view. Fig. 6 is a plan view of a modification, showing the device open; Fig. 7 is an inverted plan view thereof, and Fig. 8 is a perspective view of the device closed.

The cover or holder strip 1 may be of any suitable material, such as thin, flexible, 65 cardboard, divided by pairs of creases, scoring or folding lines 2 and 3, into three parts or members 4, 5 and 6, two of which are of substantially equal dimensions and the third a little shorter than the others, and herein referred to as the flap or cover flap. Between the pairs of lines 2 and 3 are the parts 7 and 8, herein referred to as the hinge members. By the construction described, when the part 4 is folded over toward part 5, the hinge member 7 intervenes to separate the parts, and when the flap 6 is folded over upon the part 4, the hinge member 8 serves a like purpose, so that, as seen in Fig. 5, the folded device is of parallel or rectangular, 80 instead of wedge form. To the part 4 is fastened the card 9 of matches of any suitable construction preferably having an integral body portion, the heads being arranged at the outer or free end of the part. 85

10 is a metallic staple having spaced prongs and a connecting head, with its prongs passed through the holder strip and engaging the body portion of the match card to immovably fasten the card to the part 4, its outer or head end 11 being arranged on the outside of the strip and preferably turned over or offset from the prongs so as to extend lengthwise of the strip, thereby clenching the fastening and yet sufficiently free to afford a clip or hold down to engage the free end of the flap 6 when it is folded over as shown in Figs. 3 and 5 and tucked beneath the head and between it and the adjacent strip beneath it. The part 5 also has a card of matches 12 applied to it in any severable way. One or more striking surfaces 13, 14, may be applied to the book, either both of them on the outside, as shown in Fig. 2, or one of them on the outside and the other on the inside as shown in Figs. 6, 7 and 8. In any case these striking surfaces are so arranged as to be beyond possible contact with the match heads, thereby avoiding danger of accidental ignition. 110

Any desired number of match cards may be arranged on the holder. In Figs. 1 and 5 there are two such cards, while in Figs. 6 and 8 there is only one.

- 5 Figs. 6 to 8 show also a modified form of the head of the card-fastening staple, same being angular, as shown at 15, instead of curved as shown in Figs. 1 to 3. Either form affords a very secure fastening for the 10 match cards and a firm holding grip upon the cover flap and prevents its accidental escape. Other variations of this metallic spring grip are within the scope of the invention.
- 15 As previously indicated, it is possible to make these strips to include many or few cards of matches, or even one card; and these and other variations are deemed to be within the principle of the invention as 20 herein explained and claimed.

What I claim is:—

1. Book matches, comprising a foldable strip including a closing flap or cover, a card of matches having a series of match splints 25 and an integral body portion applied to the inside of said foldable strip, and a metallic staple comprising a head and spaced prongs, having its prongs passed through said strip and engaging the body portion of said card 30 of matches and clenched to fixedly and im-

movably secure the card of matches upon said strip, the head of said staple being arranged transversely upon the outside of said strip and serving as a clip to engage the free end of the closing flap to hold the 35 strip in folded condition.

2. Book matches, comprising a foldable strip including a closing flap or cover, a card of matches having an integral body portion applied to the inside of said foldable strip, and a metallic staple comprising a head and spaced prongs, having its prongs passed through said strip and engaging the body portion of said card of matches and clenched for fixedly and immovably securing said card of matches in place upon the strip and having its head arranged transversely on the outside of said strip and offset from the prongs of the staple and extending longitudinally of the strip and 40 adapted to engage the free edge of the closing flap or cover to hold the book in folded condition.

In testimony whereof I have hereunto set my hand this 25th day of November, A. D. 55 1914.

LUCIAN E. PARKER.
